JOHN ALBERTI, OF NEW YORK, N. Y., ASSIGNOR TO INTERNATIONAL CORK COMPANY,
OF BROOKLYN, NEW YORK, A CORPORATION OF NEW YORK.

CLOSURE FOR RECEPTACLES.

1,234,711.

Specification of Letters Patent.

Patented July 31, 1917.

Original application filed June 23, 1913, Serial No. 775,353. Divided and this application filed August 26, 1913, Serial No. 786,700. Renewed December 23, 1916. Serial No. 138,683.

To all whom it may concern:

Be it known that I, JOHN ALBERTI, a citizen of the United States, and resident of the city of New York, in the county of Kings 5 and State of New York, have invented certain new and useful Improvements in Closures for Receptacles, of which the following is a specification, the same being a division of application for U. S. Letters 10 Patent, Ser. No. 775,353, filed June 23, 1913.

The present invention relates to closures or stoppers for bottles, cans and like receptacles; more particularly it pertains to closures of the cap variety, including those 15 termed "crown corks."

Closures of this type comprise usually three parts, that is a metallic cap or crown to be locked to the neck of the bottle, etc., a sealing disk or packing of cork or the like, 20 and a fusible impervious cementing medium, for instance in the form of a disk, interposed between the metallic cap and the sealing disk.

In manufacturing these closures, the cementing material is fused and the assembled closure subjected to pressure before the cementing material sets or hardens, whereby it 25 unites the sealing disk with the metallic cap. Usually the three parts mentioned are first assembled, and the closure, as a whole, then subjected to heating action to fuse the cementing material, pressure being applied 30 afterward. In other cases, the caps contain only the cementing material when heat is applied to the same, the sealing disks being 35 inserted subsequently.

Generally the cementing medium is composed of copal gum, resin and a waxy substance, or of copal gum and some other suitable material or materials. To properly 40 fuse the cementing medium, the outer surface of the metallic cap is subjected to heating action of at least 300° Fahrenheit, the heat being conducted by the cap to the cementing medium. It has been found that 45 the extent of exposure to heat to properly fuse the cementing medium is always ruinous to decorated caps inasmuch as it affects the paint used in decorating the same, and otherwise defaces the caps. Even plain 50 caps cannot well be heated to such extent inasmuch as they are transported from one place to the other on the assembling and uniting machine at a speed which sometimes

prevents the proper extent of exposure to 55 heat which is required to fuse both faces of the cementing medium, the latter being usually in the form of a paper disk which has been soaked in or carried through a molten mixture of the substances above mentioned. 60

In practice it has been found that if a closure of this type is exposed to moist heat, as for instance in pasteurizing bottled beer, etc., the union between the sealing disk and the metallic cap is affected to a great degree, and in some cases, in fact, destroyed. 65 If too much of the fusible cementing medium is contained in a closure and the liquid contents of the bottle subjected to heat, the cementing medium exudes toward the working face of the sealing disk and drips into the liquid contents of the bottle, forming 70 "beads" therein.

In manufacturing these caps, in many cases the cutting mechanism of the assembling machine fails to deposit a disk of cementing medium into a cap, in which case, obviously, a union cannot be made between the sealing disk and the metallic cap. Furthermore when the assembled closures are 75 subjected to heating action, the sealing disks, if they are of cork, lose to some degree their toughness by reason of the high temperature to which they are subjected, or they may be rendered entirely useless if they are of the 80 artificial or composite type, inasmuch as the latter contain a binding material, which is 85 rendered entirely useless if they are of the 90 artificial or composite type, inasmuch as the latter contain a binding material, which is 95 rendered entirely useless if they are of the 100 artificial or composite type, inasmuch as the latter contain a binding material, which is 105

The main object of the present invention is to produce a closure for receptacles, in which a firm union between the metallic cap and the sealing disk or packing is obtained by the aid of a liquid or viscous cementing medium, which is coagulated and rendered insoluble by subjecting the closure to heat 95 maintained substantially below the boiling point of water, that is to say at a point which is considerably below the heat necessary in all processes heretofore in use. All defects of the closures above described are 100 obviated.

With these and other objects in view, which will more fully appear as the nature of the invention is better understood, the same consists in the combination, arrangement and construction of parts herein-after fully described, pointed out in the appended claims and illustrated in the ac-

companying drawings, it being understood that many changes may be made in the size and proportion of the several parts and details of construction within the scope of the appended claims without departing from the spirit of the invention.

One of the many possible embodiments of the invention is illustrated in the accompanying drawings, in which:—

13 Figure 1 is a plan view of a closure constructed in accordance with the present invention; Fig. 2 is a central vertical section taken through the same; and Fig. 3 is a central vertical section taken through a modified closure.

15 In the drawings a bottle closure of the crown cork type has been shown for purposes of illustration. It is, however, obvious that the invention may be applied to 20 any and all closures of the cap variety, the forms of the metallic caps of the closures being entirely immaterial as far as the invention is concerned, as will appear from the following description.

25 Referring now more particularly to Figs. 1 and 2 of the drawings, the numeral 10 indicates a cap comprising a substantially cylindrical head 11, and a corrugated flange 12, which is adapted to be locked, in the 30 well known manner, to the exterior of a bottle neck. This cap is made, as usual, of thin sheet iron coated with tin, the outer face of its head being sometimes decorated. Within the cap is disposed a sealing disk or 35 packing 13 of cork or the like, which is united with the cap by an interposed cementing medium, denoted by the numeral 14. The nature of this cementing medium will be described hereinafter.

40 In manufacturing these closures, the metallic cap is charged with a cementing medium, either liquid or viscous, coagulable by heat, and possessing further chemical properties, hereinafter fully described. The sealing disk or packing of cork or the like is 45 then inserted into the cap on top of the cementing medium, the assembled closure subjected to pressure and exposed to heat, which will cause the cementing medium to coagulate and to unite the metallic cap with the sealing disk or packing. Instead of charging 50 the cap with the cementing medium, obviously that face of the sealing disk may be coated therewith which is to contact with the 55 inner face of the cap.

56 The cementing medium is, preferably, either of a type which is coagulated and rendered insoluble by heat alone, or by heat and suitable chemical agents mixed therewith. 60 Certain proteids or substances made up partly of proteids, such as albumin or blood, may be used for the purpose at hand, the same being coagulated and rendered insoluble by heat. Albumin has been found to be 65 particularly adapted for use in connection

with the present invention, it being inodorous, tasteless, soluble in water before use, and coagulates at 140° Fahrenheit. The assembled closures can be subjected to pressure without changing the chemical properties of the albumin, and when they are, after the pressure is applied and while it is maintained, subjected to heat, the albumin is easily coagulated and rendered insoluble, and forms an effective cementing medium 75 for uniting the parts of the closures. Substances of the second type mentioned are, for instance, gelatin and glycerin, which, when mixed with an aqueous solution of formaldehyde and heated, coagulate and are 80 rendered insoluble.

If necessary, a paper or other disk may be interposed between the metallic cap and the sealing disk. A structure of this type is shown in Fig. 3 of the drawings, comprising 85 a cap 15, having disposed therein a disk 16 of paper or similar material, that is united with the cap by the cementing material above described, and denoted by the numeral 17. On top of this disk is placed a sealing 90 disk 18 of cork or like material, joined with the said disk 16 by cementing material 19 of the character above specified. In such cases the cap is first charged with a suitable quantity of cementing medium, the paper 95 disk placed on top of it, the exposed face of said paper disk coated with the cementing medium, after which the sealing disk is deposited into the cap, and the assembled closure subjected to the treatment abovementioned, or the paper or other disk may be coated before insertion with the cementing medium.

The pressure on the closure is, preferably, maintained only until the cementing medium has been properly coagulated. The coagulation results in a firm union between the parts of the closure, such union being instantaneous, particularly when albumin is used. If found necessary, obviously the 110 pressure on the parts of the closure can be maintained for some time after coagulation.

It is to be observed that the temperature at which the cementing medium is coagulated is considerably below the heat applied 115 in all processes of manufacture heretofore in use, and for this reason the process herein described can be used in connection with plain and decorated caps, and with all sealing disks, whether they be of cork or the 120 artificial or composite type. Inasmuch as the cementing medium is rendered insoluble, the union between the parts of the closure will not be destroyed if it is subjected to moist heat, for instance when pasteurizing 125 bottled beer, etc. The cementing medium forms an insoluble and impermeable film between the sealing disk and the metallic cap, wherefore the contents of a bottle cannot work their way through the cementing me- 130

dium, nor is the latter able to drop into the contents in the form of "beads," or otherwise. A better and more effective union is formed for the reason that the cementing medium adheres to metallic caps irrespective of the fact whether the caps are spotted with greasy or oily matter or not. The cementing media heretofore in use were defective in this respect, inasmuch as they did not adhere to greasy or oily metallic surfaces.

It is obvious that, while herein specified cementing materials have been described, others may just as well be made use of without departing from the spirit of the invention, which lies mainly in the production of closures of the cap variety, including crown corks, wherein the metallic caps and sealing disks are united by the aid of a cementing medium which is coagulated and rendered insoluble by heat. It is intended to include in the appended claims in the term "cementing medium" such as are coagulated and rendered insoluble by heat either by reason of their chemical properties, or by the aid of suitable chemical agents mixed therewith. It is furthermore intended to include in the term "cementing medium" the said medium alone or a disk of paper or other material coated therewith.

What I claim is:—

1. A closure for receptacles comprising a

metallic cap, a sealing disk, and an interposed heat-coagulated cementing medium.

2. A closure for receptacles comprising a metallic cap, a sealing disk, and an interposed cementing medium coagulated and rendered insoluble by heat.

3. A closure for receptacles comprising a metallic cap, a sealing disk or packing of cork or the like, and an interposed cementing medium composed of heat-coagulated albuminous substance.

4. A closure for receptacles comprising a metallic cap, a sealing disk, and an interposed liquid cementing medium rendered insoluble by heat.

5. A closure for receptacles comprising a metallic cap, a sealing disk, and an interposed cementing medium rendered insoluble by heat.

6. A closure comprising a shell and a sealing disk, the shell and disk being stuck together by an interposed layer of fibrous material carrying a sticking material which is set by heat.

Signed at New York, in the county of New York, and State of New York, this 19th day of August, A. D. 1913.

JOHN ALBERTI.
